WILLIAM JAMES HARE AND JAMES PETER HARE, OF TORONTO, CANADA,
ASSIGNORS OF FORTY-FIVE ONE-HUNDREDTHS TO HERBERT WILLIAMS,
EMMA WILLIAMS, ALICE HARE, AND THOMAS HARE, OF TORONTO, CANADA.

ELECTRIC TRAIN-SIGNAL.

SPECIFICATION forming part of Letters Patent No. 745,277, dated November 24, 1903.

Application filed July 11, 1902. Serial No. 115,182. (No model.)

To all whom it may concern:

Be it known that we, WILLIAM JAMES HARE and JAMES PETER HARE, of the city of Toronto, in the county of York, Province of Ontario, Canada, have invented certain new and useful Improvements in Electric Train-Signals, of which the following is a specification.

The object of our invention is to devise means for automatically conveying warning-signals to the engineers of trains which come within a safe limit of distance of one another; and it consists, essentially, of a source of electric current carried by one engine and connected with two parallel insulated conductors extending along the track and of an electric bell on the other engine also connected with the said conductors, so that when the engines come near enough together to enable the electric potential to overcome the resistance of the conductors the bell rings, and thus warns the engineer. When a warning is to be given on each engine, a source of electric current and a bell are connected in series on each engine, substantially as hereinafter more particularly described and then definitely claimed.

Figure 1 is a side elevation of a portion of a locomotive equipped with our electric signal apparatus, the portions of the locomotive being shown in dotted lines and the signaling apparatus in full lines. Fig. 2 is a side elevation of a commutator with the front-side of its casing removed. Fig. 3 is a plan view of the same. Fig. 4 is an end elevation of the same. Fig. 5 is a perspective view of a contact-wheel and its brushes. Fig. 6 is a perspective detail of a section of the electrical rails or conductors. Fig. 7 is a diagrammatic view showing the arrangement of the apparatus.

In the drawings like letters of reference indicate corresponding parts in the different figures.

The general arrangement of our apparatus will be best understood by reference to Fig. 1, in which A is a source of electric current, either a battery or dynamo; B, an electric bell; C, a contact-wheel, formed in two insulated parts, respectively, engaging the paral-

lel insulated electric conductors or rails D D', 50 and E E', insulated wiring connecting in series the source of current, the electric bell, and the halves of the contact-wheel. (See Fig. 7.) As the conductors D D' are insulated from one another, no current can flow 55 through the circuit. If, however, another engine equipped with the apparatus just described comes sufficiently close for the potential of the source of current A to overcome the resistance of the conductors between 60 the two engines, the current will flow out from the first engine through the conductor D to the second engine, through the circuit of the second engine to the conductor D', thence back to its starting-point, incidentally ringing the bells in each circuit, and thus warning each engineer of the fact that he is approaching another train.

It will be seen that if warning is desired in one engine only the bell might be omitted 70 from one circuit and the source of electricity from the other; but such an arrangement would not be commercially practicable, as no assurance could be given that two engines drawing near to one another would be 75 equipped with the proper complementary apparatus nor could absolute safety be insured when only one engineer was aware of the possibility of a collision. We therefore propose to invariably equip each engine with 80 both a source of current and a bell in the same circuit.

When each engine is equipped with a source of current connected with the conductors D D', it may happen that the positive terminal 85 of each source of current will be connected with one of the conductors and the negative terminal of each source of current with the other, in which case as the sources of current are working against one another no current 90 could flow in the apparatus of either engine and no warning would be given to either engineer. We therefore include in the circuit of either engine a commutator F, arranged to produce a rapid and constant alternation in 95 the direction of the current given out by the source A. With a constant change in the direction of the current carried to the conduc-

tors D D', it must happen that at least half the time the sources of current on engines nearing one another are working in a proper direction to admit of the passage of a current 5 through the entire double system, causing the proper ringing of the bells to warn the engineers.

While any commutator might be adopted for the purpose of our invention, we prefer 10 to use the special form shown in Figs. 2 and 3 and 4. In these views G represents a suitable casing secured below the body of the engine. In this casing is journaled the rock-shaft H, having insulated collars I I' secured thereto. On each collar are formed projections J J'. Contacting with the curved surfaces of the collars are the spring-actuated brushes K K' of any suitable construction. With these brushes the wires E E' are 15 respectively connected. Adjacent to the collars I I' and on each side thereof we provide four standards L. On these standards are pivoted the yielding contact-pieces M M'. The tails of these contact-pieces are engaged by 20 the coil-springs a, normally tending to force them up. Their upward motion is limited by means of the rods b, secured to the bases of the standards and extending through loosely-fitting holes in the tails. Suitable adjusting-nuts are provided above the tails, the ends of 25 the rods being screw-threaded to permit of the nuts being adjusted to adjust the positions of the contact-pieces. The standards L are necessarily in electrical connection with 30 the contact-pieces and are cross-connected by means of the wires c c'. As will be seen on reference to Fig. 2, when the rock-shaft is in its central position the projections J J' are all out of contact with the yielding contact-pieces M M'. If, however, the rock-shaft be 35 rocked to the left, the projections J' are brought into contact with the contact-pieces M'. Current may then flow (supposing the left-hand end of the wire E to be connected 40 with the positive terminal of the source of current) through the wire E, the brush K, collar I, the contact-piece M', engaged with the projection J' of the said collar, through the standard of the said contact-piece, and 45 into the right-hand continuation of the wire E. The return is through the right-hand section of the wire E', through the standard L of the far contact-piece M', the projection J', the collar I', through the said collar, and 50 through the brush K' to the left-hand section of the wire E'. If, now, the rock-shaft be rocked to the right to bring the projections J into contact with the yielding contact-piece M, the direction of the current will be as follows: 55 through the left-hand section of the wire E', through the brush K into the collar I, through the projection J thereon into the near contact-piece M, through its standard L, through the wire c to the standard of the 60 far contact-piece M', and thence into the right-hand section of the wire E'. The re-

turn is through the right-hand section of the wire E to the standard of the near contact-piece M', thence through the wire c' to the standard of the far contact-piece M, through 70 the said standard and contact-piece, through the projection J of the collar I', through the said collar into the brush K', thence to the left-hand section of the wire E'. Thus by rapidly rocking the shaft H a rapid alternation 75 may be made in the direction in which the current flows or may flow through the wires E E'. The shaft may be rocked in any suitable manner. We prefer, however, to connect an eccentric N to one of the axles of 80 the locomotive. On the end of the rock-shaft H we secure an arm O, connected with the eccentric by the eccentric-rod d. Thus when the engine is running the desired alternation in the direction of the current is effected. 85

The wheel C, by means of which contact is made with the conductors D D', is best understood by reference to Fig. 5. The essential parts of this wheel are the two insulated metal disks P P'. Each of these, however, is 90 electrically connected, respectively, with one of the sleeves Q Q', insulated from the axle or bearing of the wheel. The axle of this wheel is journaled in boxes R, suitably supported by the truck of the pony-wheels of the 95 locomotive. These boxes are preferably made vertically movable, as shown, and are normally held down by springs e, so that the wheel may be given a yielding contact with the conductors D D'. Contacting with the 100 sleeves Q Q' are the spring-actuated brushes S S'. These brushes are preferably carried on arms T, pivoted at f on any suitable part of the truck of the pony-wheels of the locomotive. A contact is thus provided between 105 the brushes and the sleeves, which will be maintained under all inequalities of the conductors and will not be disturbed by vibrations or other motions of the locomotive or truck. 110

In order to provide means for testing the apparatus, we connect the brushes S S', by means of the wires g g', with an electric lamp U. Included in this circuit is a switch h. By throwing in this switch a circuit is established from the source of current through the lamp. If the lamp lights up when the switch is thrown in, the engineer knows at once his apparatus is in working order. If the lamp does not light, something is wrong and steps 115 will be taken to put the apparatus in order or to take extra precautions to avoid collisions. 120

From the above description it will be seen that it is impossible for two trains to come 125 closer together than is safe without warning being immediately given to each engineer, and this when the trains are drawing together from opposite directions or in the same direction or even when one is at a standstill. 130

If all the wheels of both trains were insulated, the ordinary rails might be used in-

stead of the conductors D D'; but such an arrangement would not be commercially practicable.

If it were made a settled rule that all trains going in one direction had the positive terminals of their sources of current connected with one conductor and those of the trains going in the other direction with the other conductor, the commutators could be dispensed with; but in such a case warning-signals would only be given of a threatened end-on collision, and rear-end collisions would be liable to occur. Still such an arrangement would be of considerable value and falls within the scope of our invention. Much the same results would be obtained if all trains going in one direction were provided with commutators and trains going in the other direction were either without them or had them out of gear; but all such arrangements, though they have their value, are defective, and we prefer to equip each engine or train with a complete outfit, as described.

The distance at which signals will be given depends entirely on the relation of the potential of the current from the source of electricity to the resistance of the conductors D D'—the greater the potential the greater the length of conductor through which current may be forced. We consider that for safety the bells should ring when the trains are not less than one mile apart. While we speak of bells, of course it will be understood that any other signal-receiving apparatus may be employed with or instead of the bells. So, too, while for convenience we employ the words "engine" or "train," it will be understood that the invention is applicable to rolling-stock of all kinds.

Our invention not only signals the nearing of two trains, but an engineer can be informed of an open switch or an obstruction by the simple device of bringing the two conductors into electrical connection, when a warning is at once rung. By making and breaking the connection a regular code of signals might be employed. It is really as important to warn an engineer that a switch is not set right for him as it is to warn him of the danger of a collision, and the conductors could easily be arranged at switches to come into electrical connection when the switch is set the wrong way for an approaching train.

We consider our system much superior to the present electric block system, inasmuch as all the apparatus is within the immediate reach and control of the engineer and it is not necessary to provide for maintenance of electrical apparatus all along the track, often at considerable distance from stations or other headquarters from which repairs must be effected.

The rails or conductors D D' are the only parts of the apparatus requiring to be permanently laid in connection with the track. These are best seen in Fig. 6. The two separate conductors are there shown secured to the top of a longitudinal wooden stringer V, a portion of which divides the one conductor from the other. This stringer is of such a height as to raise the conductors above the level of the ordinary rails of the track, so that the wheel C will clear these rails at switches and crossings.

The details of construction of this invention might be varied considerably from those illustrated and described without departing from the spirit of our invention as set out in the accompanying claims.

What we claim as our invention is—

In electrical signaling apparatus for trains and the like, a pair of insulated conductors extending lengthwise of the track in close proximity to one another; a trolley-wheel formed in two parts insulated from one another, one running on one conductor and the other on the other conductor; vertically-movable bearings for the said wheel carried by a train; sleeves connected respectively with the parts of the trolley-wheel; brushes engaging the said sleeves; arms carrying the said brushes and pivoted on a suitable stationary part; a source of current carried by the train and having its terminals connected respectively with the parts of the trolley-wheel; and signal apparatus in circuit with the trolley and source of current in combination with means for forming an electrical connection between the two conductors, substantially as described.
